UNITED STATES PATENT OFFICE.

MATTHEW CUMMINGS, OF BOSTON, MASSACHUSETTS.

SMOKE-CONSUMING FURNACE

1,368,389.

Specification of Letters Patent. Patented Feb. 15, 1921.

Application filed March 30, 1918. Serial No. 225,649.

To all whom it may concern:

Be it known that I, MATTHEW CUMMINGS, a citizen of the United States, residing at Boston, county of Suffolk, State of Massachusetts, have invented an Improvement in Smoke-Consuming Furnaces, of which the following description, in connection with the accompanying drawing, is a specification, like characters on the drawing representing like parts.

This invention relates to an improved furnace by which coal may be burned in a very economical manner without the production of any smoke. The furnace is of the known type having an endless chain or movable grate. In my improvement, I provide a coking grate in front of the endless chain grate and situated below the top of the latter, and also provide means for delivering the green coal onto the coking grate and then transferring said coal after the gases have been driven off therefrom onto the endless chain or movable grate.

In the operation of my improved furnace after the coal on the coking grate has been completely coked, the movable grate is advanced thereby to present a fresh grate surface at its front end directly in the rear of the coking grate. The top portion of the coked coal is then transferred from the coking grate onto the fresh grate surface where it continues to burn as coke. Only the top portion of the coked coal is thus transferred from the coking grate and hence after the transfer there will still remain on the coking grate a bed of burning coke. Green coal is then deposited and allowed to remain on this bed of burning coke until all gases therein have been liberated and driven off and burned, after which the movable grate is again advanced and the upper portion of the coked coal is again transferred to the fresh grate surface, this being done in such a way as to leave a bed of burning coke on the coking grate, as above described. An added quantity of green coal is then deposited on the coking grate and the above operations are repeated. The gases which are driven off from the green coal are consumed and give up their heat units as they pass over the burning coke on the movable grate.

One advantage resulting from the use of this furnace is that the green coal is always delivered onto a bed of burning coke and hence the gases will be liberated from the green coal in a most economical manner.

Moreover, since these gases are generated entirely in front of the movable grate, they will be burned while passing over the movable grate and before they reach the bridge 60 wall at the end of the combustion chamber.

In my improved furnace the space occupied by the coking grate constitutes a gas retort in which combustible gases are generated.

In order to give a better understanding of my invention I have illustrated in the drawings more or less diagrammatically a furnace embodying my invention.

Figure 1 is a longitudinal vertical sectional view of a furnace made in accordance with my invention;

Figs. 2, 3 and 4 are similar views showing different steps in the operation of the furnace;

Fig. 5 is a sectional view on the line 5—5, Fig. 1.

The furnace herein shown is provided with an endless chain or traveling grate 1 which operates about sprocket wheels or 80 their equivalents 2. The space 3 above the grate constitutes the combustion chamber and the space 4 below said grate constitutes the ash-pit. Situated in front of the endless chain grate is a stationary coking grate 85 5 which is situated below the upper surface of the endless chain grate. This coking grate 5 extends from the front of the endless chain grate to the furnace front 6. A furnace embodying my invention may be 90 used for any desired purpose and that herein shown is one constructed to heat a boiler 7.

The furnace herein shown is constructed so that green coal may be deposited on the 95 coking grate 5. This may be done either by hand or automatically. I have herein shown a construction including a hopper or feed chute 8 situated above the coking grate and provided with a gate 9 which normally 100 closes the chute or hopper, but which may be withdrawn to allow the coal to be delivered onto the coking grate. The furnace is also provided with a transferring device in the form of pushers 10 situated to push or 105 transfer part of the coke on the coking grate to the endless chain grate. This pusher or transpeller 10 is in the form of a reciprocating plunger which may be operated by any suitable means, not shown, and the 110 lower side thereof is situated slightly above the level of the top surface of the grate 1.

Since the coking grate 5 is several inches below the top of the endless chain grate, a space of several inches will exist between the transferring device 10 and the coking grate 5.

When the apparatus is in use there will be a body of burning coke 11 on the endless-chain grate, and another body of burning fuel on the coking grate 5. The green coal which is delivered to the furnace will be deposited on the coking grate 5, and this green coal will gradually become coked, during which process combustible gases will be driven off therefrom. The gases which are thus driven off from the coking coal will pass through the combustion chamber over the burning coke 11 and will become consumed before they pass over the bridge-wall 12.

After the combustible gases have been driven off from the fuel on the coking grate 5, the endless-chain grate is advanced either by hand or automatically, thereby to bring a fresh or clear grate surface 13 at the front end of the endless-chain grate, as shown in Fig. 2. After this fresh grate surface has been provided, the upper portion 14 of the body of fuel on the coking grate 5 is transferred onto the fresh grate surface 13 so as to fill the grate 1, as seen in Fig. 3. This transfer will leave a body 15 of burning coke still on the coking grate 5. After the transfer has been effected, a body of green coal 16 will be deposited on the burning coke 15 and allowed to remain there until all the combustible gases have been driven off therefrom, such gases being consumed during their passage through the combustion chamber. After the body 16 of green coal has been coked, then the movable grate is advanced again to provide a fresh grate surface and the coked body of coal 16 is transferred to said fresh grate surface, and more green coal is deposited on the coking grate, etc.

With this sequence of operations there will always remain a body of burning coke on the coking grate 5 so that the green coal is always deposited on a bed of burning coke. This is very advantageous because by so doing the combustible gases in the green coal are liberated in the most economical way.

The space at the front end of the furnace where the coking grate is situated has the function of a gas retort or gas producer in which combustible gases are produced, and these combustible gases are entirely consumed in the combustion chamber. The result is that all the gases from the coal are burned in the furnace and no combustible gases will be wasted by passing to the smoke

stack without being consumed. This makes a smokeless furnace.

Another advantage of my improved furnace is that it can be stoked with a minimum expenditure of labor. The method of handling the coal eliminates all necessity for using a slicing bar and the only attention which the furnace needs is that required to advance the movable grate, transfer part of the fuel on the coking grate to the movable grate and deliver fresh fuel to the coking grate.

My improved furnace has the further advantage that the coal can be burned with a minimum production of clinkers.

I may if desired provide a furnace front with doors 17 through which suitable implements may be inserted for the purpose of evenly spreading the green coal 16 onto the body of burning coke.

I have not illustrated herein any mechanism for operating the grate 16 or reciprocating the pushers 10 as any suitable devices adapted for this purpose may be employed.

I claim:

1. In a furnace, the combination with an endless-chain grate having its upper run in a single plane, of a coking grate situated entirely in front of the endless-chain grate and below the level of the upper run thereof, means to deliver fuel onto the coking grate, means to transfer periodically onto the endless-chain grate that portion only of the fuel on the coking grate which is situated above the level of the endless-chain grate whereby after each transfer there will be left a body of burning coke on the coking grate onto which green coal may be delivered.

2. In a furnace having a combustion chamber, an endless chain grate and sprocket wheels around which said grate passes, the combination with said grate, of a coking grate situated in front of the front sprocket wheels of the endless chain grate and below the level of the top surface of said grate, a reciprocating plunger situated slightly above the level of the endless chain grate and constructed to have a reciprocating movement over the coking grate whereby inward movement of the plunger forces onto the endless chain grate that portion only of the fuel on the coking grate which is situated above the level of said endless chain grate, the portion of the fuel on the coking grate below the level of the endless chain grate remaining as a body of burning coke, and means to deliver green coal onto said body of burning coke.

In testimony whereof, I have signed my name to this specification.

MATTHEW CUMMINGS.
